D. C. GENTRY,
PORTABLE SHOT FIRING DEVICE,
APPLICATION FILED APR. 2, 1918.

1,304,306.

Patented May 20, 1919.

UNITED STATES PATENT OFFICE.

DEMAUS C. GENTRY, OF VINCENNES, INDIANA.

PORTABLE SHOT-FIRING DEVICE.

1,304,306.

Specification of Letters Patent. Patented May 20, 1919.

Application filed April 2, 1918. Serial No. 226,207.

To all whom it may concern:

Be it known that I, DEMAUS C. GENTRY, a citizen of the United States, residing at Vincennes, in the county of Knox and State 5 of Indiana, have invented certain new and useful Improvements in Portable Shot-Firing Devices; and I do hereby declare the following to be a full, clear, and exact description of the invention, such as will enable others skilled in the art to which it 10 appertains to make and use the same.

This invention relates to shot firing devices and more particularly to a portable apparatus of this character, preferably for use 15 in gaseous coal mines, and the primary object of the invention is to provide an inexpensive device which can be conveniently operated from any electric current carrying wire, such as an electric light or power wire. 20 A further object of the invention is to provide a shot firing device embodying a plurality of time controlled circuit making contacts and means for controlling the admission of electric current to said contacts.

25 A still further object of the invention is to provide a shot firing device embodying a carbon or other brush and a plurality of such contacts for successive engagement with the brush to close the shot firing circuits successively, said brush and contacts by virtue 30 of their composition resisting adhesions when engaged with each other while the explosive is being fired by the shorting of the circuit.

A still further object of the invention is 35 to removably position the shot firing mechanism within a casing which will prevent the admission of gases to the apparatus and thus eliminate the possibility of an explosion therefrom.

40 A still further object of the invention is to arrange fuses between the carbon or other contacts and the shot firing wire binding posts which will prevent the blowing of the fuses in the main line in case of a short in 45 the circuit of the shot firing wires.

A still further object of the invention is to provide means for limiting the rotatable movement of said time controlled contacts, allowing ample time or intermission between 50 shots.

With these and other objects in view as will appear as the description proceeds, the invention comprises the various novel features of construction, combination and arrangement of parts as will be fully de-

scribed hereinafter and afterward specifically claimed.

Referring to the drawings,

Figure 1 represents a side elevation of the device, 60

Fig. 2 represents a view of the mechanism removed from the casing, and the wiring connected thereto.

Fig. 3 represents a transverse sectional view showing the contacts. 65

Fig. 4 represents a transverse sectional view showing the fuses of the contacts, and

Fig. 5 represents a sectional elevation of an improved shot firing cap.

In order that the construction and operation of the invention may be readily comprehended by those skilled in the art to which the invention relates, I have illustrated an approved embodiment thereof in the accompanying drawings and will now 70 proceed to fully describe the same in connection with said drawings in which 1 is a portable casing provided with a suitable handle and into which the apparatus may be inserted and removed whereby access may be 75 had to the mechanism.

The apparatus is mounted upon a base board 2 of insulation attached to and supported by the end board 3, which also is of suitable insulating material. This end board 80 serves to close the open end of the casing and is adapted to be secured thereto by a hasp 4 on each side.

5 is an alarm clock attached on the base board and provided with a laterally extending stop 6. A key shaft 7 is connected to the alarm key arbor of the clock and connected to rotate with it. 8 is an arm that projects laterally from the key shaft and is adapted to engage the stop 6 to limit the rotation of the key shaft to one revolution. As shown, the key shaft extends through the end board 3 and is provided with a wing nut 9 to enable the apparatus to be rewound or set after each operation. 95

A plate or dial 10 of insulating material is fixed on the key shaft 7 and is provided circumferentially for three fourths of its circumference with a plurality of carbon or other contacts 11 spaced apart adjacent the 105 periphery of the plate. Each of these contacts is connected by a fuse 12 to an adjacent binding post 13 arranged on the side of the plate 10 opposite to that on which the contacts 11 are positioned. Each binding 110

post 13 has a shot firing wire 14 connected to it and to a corresponding binding post 15 on the end board 3, enough slack being left in said wires to permit the dial to freely 5 rotate one revolution.

These contacts 11 are adapted to be successively engaged by a carbon or other brush 16 carried by a spring pressed arm 17 that is pivotally mounted on the base board 2. 10 The brush projects into the path of movement of said contacts 11 and normally rests in the space forming a fourth of the circumference in which there are no contacts.

A knife switch 18 is mounted on the end 15 board 3 and has connected to it one end of an electric current line wire 19 which may be any convenient current carrying wire in the immediate vicinity in which it is desired to use the shot firing device, such for instance 20 as an electric light or power line wire. Fuse plugs 20 of higher fusibility than the fuse wires 12 are placed in the line wire 19. A wire 21 connects the switch 18 with the brush 16.

25 In Fig. 5 will be seen a detail view of an improved form of cap which comprises two pieces of adhesive or other fabric 23 and 24 securely fastened together over the terminal ends of the shot firing wires, which latter 30 are connected by a low fusible resistance wire 25. This cap is primarily designed for use in connection with the old fashioned black powder and will effectively explode the powder by sending a current through the 35 cap sufficient to blow the low fusible resistance wire.

In the operation of the apparatus each shot to be fired has one of the shot firing wires 14 connected to it by a wire 26 and the 40 return wire 27 so that when the switch 18 is closed and the contacts 11 are revolved to successively engage the brush 16, the circuits will be closed in successive order. When it is desired to set the apparatus, the key shaft 7 45 is turned until the arm 8 comes into engagement with the stop 6 which action will rotate the plate 10 until the brush rests in the one fourth circumferential space between the contacts. The switch 18 is then closed. 50 When the alarm goes off and the shaft 7 begins to revolve, the contacts 11 will be brought into successive engagement with the brush 16 to complete the shot firing circuits in succession. The shaft will revolve until 55 it again engages the stop 6 which will limit the rotation of the plate 10 to one revolution.

After all the shots have been fired, the switch 18 can be opened and the device rewound or set by turning the thumb nut 9.

It is to be of course understood that any 60 number of contacts may be used to suit the purpose desired.

From the foregoing description taken in connection with the accompanying drawings, it is of course to be understood that 65 while I have described the principle of operation of the invention, together with the device which I now consider to be the best embodiment thereof, I desire to have it understood that such changes in construction and 70 arrangement of parts may be made when desired as are within the scope of the appended claims.

Having thus described my invention what I claim as new is:— 75

1. A portable shot firing device embodying a supporting member, an arcuate series of contacts carried by said member, a brush to successively engage said contacts, said member and brush being mounted to rotate 80 relatively to bring the contacts into successive engagement with the brush, a time controlled mechanism for rotating said member and brush relatively, an arcuate series of binding posts carried by said member adjacent to said contacts and arranged in pairs therewith, individual fuse wires bridging the contacts and binding posts, and wires connected to and leading from said binding posts for connection with firing caps. 85

2. A portable shot firing device embodying a casing, a closure therefor, a base secured to said closure and extending within the casing, an alarm clock mounted on the base, a shaft connected to the clock and extending through said closure, a plate secured on said shaft between the clock and closure, a brush carried by the base, an arcuate series of contacts carried by said plate to successively engage said brush, binding posts carried by said closure for the connection of wires of several firing circuits, and flexible wires connecting said binding posts with the contacts and brush and disposed around said shaft between said closure and base. 100

In testimony whereof I have signed my name to this specification in the presence of two subscribing witnesses.

DEMAUS C. GENTRY.
